UNITED STATES PATENT OFFICE

EGBERT H. GOLD, OF CHICAGO, ILLINOIS.

SAFETY-VALVE FOR CAR-HEATING APPLIANCES.

No. 892,515.

Specification of Letters Patent.

Patented July 7, 1908.

Application filed March 7, 1904. Serial No. 196,977.

To all whom it may concern:

Be it known that I, EGBERT H. GOLD, a citizen of the United States, residing at Chicago, in the county of Cook and State of Illinois, have invented certain new and useful Improvements in Safety-Valves for Car-Heating Appliances, of which the following is a specification.

My invention relates to improvements in valves, especially adapted for and combined with car heating systems of the Baker type, in which a circulating medium passes through a closed circulating system. In heating systems of this type, it is usual to provide in the heating system a heater, in the form of a stove, in operative contact with a coil, which forms part of the circulating system. It is also usual to provide an expansion tank to which a riser leads from the coil within the stove.

As ordinarily constructed, the stove constitutes the emergency heater and is ordinarily out of use, the common heating device being a steam jacket or steam heater of some sort in operative contact with the circulating system and supplied with live steam from the locomotive. Consequently, as the system is commonly used, the temperature and pressure within the circulating system can never exceed that of the temperature and pressure within the train pipe, which supplies steam from the locomotive, and, therefore, no danger of overheating the circulating medium need be feared from that source.

When, however, the emergency heater is put in operation, the heating medium being fire of some sort applied directly to a coil within the emergency heater, there is always a possibility of overheating the circulating medium, of creating a dangerously high pressure, especially if steam be generated within the closed circulating system. Consequently, it is usual to provide a safety valve at some point in the circulating system and usually in connection with the expansion tank. Inasmuch, however, as the emergency heater is not commonly used, the safety valve will ordinarily remain unopened for long periods of time, with the result that safety valves of the

types commonly used will become so corroded to their seat that the pressure within the circulating system will not be sufficient to unseat the valve until it has far exceeded the danger point. This feature has been heretofore recognized and devices have been

used whereby a section of the expansion tank is weakened so that a section of the tank may be blown out bodily before the pressure within the circulating system reaches the danger point. Such a device is, of course, objectionable because it destroys the tank or the part with which the blown-out section was integral. Furthermore, such a device not only destroys a part of the apparatus, but it does not go to the source of the evil, to wit, fire in the stove, and the fire in the stove, even if an ordinary safety-valve be operated successfully, will continue to heat the already over-heated circulating system and cause a constant blow-off from the safety-valve until the water in the system is exhausted and the coil within the stove burned out. The replacing of this coil is a matter of much trouble, delay, annoyance and expense.

Among the objects of my invention, therefore, are to provide a device which shall be at all times certain and reliable in action, which shall certainly operate to relieve the pressure in the circulating system before it can reach the danger point, while, at the same time, the operation of the device will not destroy any part of the apparatus.

A further object of my apparatus is to provide means for automatically reducing the fire whenever my safety-valve operates to blow off steam or water.

These and such other objects as may hereafter appear are attained by my invention, which is embodied in what I consider its preferred form, in the drawings hereto attached, as hereinafter described.

Figure 1 is a diagrammatic view of a portion of a car heating system showing the relation of the principal parts thereof, and the manner in which the preferred form of my device is mounted. Fig. 2 is a sectional view through the preferred form of my device; and Fig. 3 is a cross-sectional view on the line 3—3 of Fig. 2, looking in the direction indicated by the arrows. Fig. 4 is a vertical cross-section through the three-way cock by means of which the water may be sent from the safety valve either into the fire box of the heater or be permitted to escape.

Like letters of reference indicate the same parts in the several figures of the drawings.

Referring by letter to the accompanying drawings, A indicates the floor of a car;

B is a boiler of the Pullman type, C, C' are the bottom corners of two unconnected cir-

5 circulating systems, each of which is inoperative connection with the heater B, one of the circulating systems being used to heat one side of the car, and the other to heat the other side of the car.

D, D' are the expansion tanks of the two circulating systems, respectively.

E, E' are the safety-valves mounted upon the tanks D, D', respectively.

10 F is a discharge pipe leading from the safety-valve E to a three-way cock G. H is a similar pipe leading from the safety-valve E' to the pipe F.

I is a pipe leading from the three-way cock 15 to the fire-box of the heater B; and J is a similar pipe leading through the bottom of the car. The three-way cock G is so arranged that it may be operated at will either to connect the pipe F with the discharge 20 pipe J or to connect the pipe F with the pipe I leading into the fire-box of the heater B.

Referring now to Fig. 2, my improved valve E is constructed as follows: A casing 1 is provided with a valve-chamber 2, and 25 with an inlet port 3 leading into said valve-chamber. A valve 4 is arranged within the valve-chamber 2 to close a passageway 5, leading to an outlet chamber 6, from which leads an outlet port 7. Between the rear 30 end of the valve-stem 8 and a cap 9, into which the valve-stem 8 is threaded, is clamped a flexible diaphragm 10. This diaphragm 10 is clamped adjacent to its periphery between the abutting faces of the casings 1 and 11, which are locked together by a ring 12.

It will be noted that the casing members 1 and 11 are provided on their clamping faces with a complementary groove and rib 40 between which the margin of the diaphragm 10 is clamped. This serves not merely to more effectively grip the diaphragm between these clamping members, but it is important that the diaphragm be accurately centered in the device to insure the proper working of the valve 4, and, in case the full clamping faces of the casing members 1 and 11 are utilized, it is also important that the diaphragm shall not project beyond these 45 clamping faces so as to engage the threads of the clamping ring 12. By this arrangement, the diaphragms can, if desired be stamped with a marginal rib which shall fit the rib and depression on the members 1 and 11, so that 50 the accurate centering of the diaphragm in the device becomes substantially automatic. Of course, any suitable complementary projection and depression on the clamping faces will serve this purpose. It will also be noted 55 that the cap 9 projects in such a manner as to engage shoulders on the casing 11 so as to serve as a stop to limit the flexion of the diaphragm 10 due to excessive pressure in the valve chamber. This will permit the diaphragm 60 to move sufficiently to open the

valve, but will prevent any strain and consequent break or permanent set of the diaphragm due to excessive pressure.

The valve 4 is normally held in position to close the passage 5 by a spring 13, which rests at one end against the cap 9 and at the other end against a button 14. The tension of this spring may be adjusted by means of a stud 15, which is threaded into the further end of the casing 11 and abuts against the button 14. The extreme end of the stud 13 is protected by a cap 16, which is screwed upon the extreme end of the casing 11. The outlet port 7 is partially closed by a plug 17, which, however, is provided with a small perforation leading from the outlet chamber 6 to the atmosphere. The inlet port 3 connects with a pipe 18, which leads to the interior of the expansion tank. The pipe F also connects with another outlet port leading 85 from the outlet chamber 6.

The operation of the device is as follows: Assuming that the circulating medium or steam generated therefrom within the circulating system has reached the pressure at 90 which the safety valve is set to operate, the pressure within the valve-chamber 2, which is in free communication with the interior of the tank D, will operate against the diaphragm 10, thereby obtaining a much larger 95 surface against which to exert its expansive force than where the pressure is exerted only against the face of the valve itself. This pressure against the large surface of the diaphragm 10 will be sufficient not only to overcome the tension of the spring 13, but also to 100 overcome any adhesion between the valve and its seat caused by long disuse and corrosion of the valve. As soon as the valve 4 is drawn from its seat, a free outlet will be 105 afforded for the circulating medium within the circulating system to pass through the valve-chamber 2, the passage 5, the outlet chamber 6, the pipe F to the three-way cock G. The three-way cock will ordinarily be so set that the pipe F will connect with the pipe I, so that the steam and water thus blown out through the safety-valve will continue from the pipe F through the three-way cock G into the pipe I, whence it will be discharged 110 directly against the fire in the fire-box of the heater B. I thus obtain a double effect. First, I allow a free outlet, whereby the pressure will be promptly reduced, and at the same time I utilize the escaping moisture to 115 reduce the fire which has brought about the excessive pressure, and thus in a short time I reduce the pressure in two ways, whereupon the valve will close and the fire will be no longer affected by the water, but will burn in its lowered condition. If, for any reason, it is preferred not to discharge the steam and water into the fire, the three-way cock G may be so set as to direct the escaping steam and water to the atmosphere through the pipe J 120

It will sometimes happen, however, that there may be a slight leakage between the valve 4 and its seat, which leakage if undetected and disregarded would ultimately result in the evaporation and discharge of all of the water in the circulating system, with consequent annoyance, delay and damage. I, therefore, have provided the plug 17, having a small passage leading to the atmosphere. If, now, there be a slight leakage, the water so leaking will not pass through the valve 4 with any force, but, trickling through, will find its way by gravity through the perforation in the plug 17 and will be discharged upon the top of the tank D, from which it will gradually trickle and evaporate. Inasmuch, as it is the common practice to use strong brine as the circulating medium in these systems, such escaping brine will soon leave a conspicuous white deposit along the top and sides of the tank D, which deposit will call attention to the fact that brine is escaping through the valve 4.

The operation of the pipe H leading from the valve E' of the pipe F will be readily understood, the effect being to give a vent to each of the circulating systems which are common in a car, and to utilize their joint discharge in reducing the fire, if desired.

While I have shown my invention embodied in what may be considered its pre-

ferred form, it will be understood that such form simply serves as a typical illustration of a convenient manner in which my invention may be utilized, but I do not by any means limit myself to the precise mechanism shown or to the precise relation of the parts shown and described.

I claim:

1. In a car heating system, the combination with a closed circulating system, of a safety valve connected therewith, a pipe leading from the blow-off of the safety-valve to a remote point, said safety valve being also provided with a separate small opening arranged to conduct leakage from the valve to an adjacent indicating point outside of the valve.

2. In a car heating system, the combination with a closed system of circulating pipes, of a fire-box heater in operative contact therewith, a safety-valve connected with said circulating pipes, a conduit leading from the blow-off of said safety valve to the fire-box of said heater, said valve being also provided with a short and constricted opening for conducting leakage from said valve to an adjacent indicating point.
